The ornamental design for a hexagonal cup, as shown and described.

DESCRIPTION

FIG. 1 is a perspective view of a hexagonal cup showing our new design;

FIG. 2 is a front view thereof;

FIG. 3 is a rear view thereof;

FIG. 4 is a left side view thereof;

FIG. 5 is a right side view thereof;

Fig. 6 is a top view thereof;

FIG. 7 is a bottom view thereof;

FIG. 8 is a bottom perspective view thereof; and,

FIG. 9 is an environmental perspective view thereof.

The broken lines are environmental or otherwise depict portions of the hexagonal cup that form no part of the claimed design.
